UNITED STATES PATENT OFFICE.

GEORGE E. DIXON, OF CHICAGO, ILLINOIS.

RADIATOR SHIELD AND FRAME.

SPECIFICATION forming part of Letters Patent No. 543,456, dated July 23, 1895.

Application filed October 20, 1894. Serial No. 526,437. (No model.)

To all whom it may concern:

Be it known that I, GEORGE E. DIXON, a citizen of Great Britain, residing at Chicago, in the county of Cook and State of Illinois, 5 have invented certain new and useful Improvements in Radiator Shields and Frames Therefor, of which the following is a specification.

In placing steam and hot water radiators 10 in rooms, halls, and other places, it is customary to locate such radiators near a wall or partition, and this invention relates to shields and frames therefor, designed to be attached to radiators for the purpose of deflecting away 15 from the wall or partition and toward the center of the room, hall, or other place in which the radiator is located the ascending currents of heated air together with the particles of dust, (if any,) carried thereby and 20 caused by such radiator.

The object of this invention is to obtain a 25 radiator-shield which can be applied to radiators already placed in operative position without interfering with or changing the radiator or its connection, and further to obtain an adjustable radiator-shield which can 30 be applied to radiators of different construction and different sizes.

Another object of this invention is to obtain 35 means whereby a radiator-shield can be extended from the top of the radiator to which it is attached to near the floor or base on which such radiator is placed.

In Letters Patent Nos. 435,290, dated August 26, 1890, and 481,900, dated August 30, 35 1892, radiator-shields, adapted to be applied to radiators and to deflect the ascending currents of air from the wall near which the radiator is placed are by me shown, described, 40 and claimed, and this invention constitutes an improvement on radiator-shields of the kind therein set forth.

In the drawings accompanying and forming 45 a part of this specification, Figure 1 is a perspective view of a radiator having a radiator-shield embodying my invention attached thereto; Fig. 2, an elevation of one end of the frame of the radiator-shield on the side thereof adjacent to the radiator; Fig. 3, a 50 sectional view on line 3 3 of Fig. 2, and Fig. 4 a longitudinal view through the post, (forming a base for the support of the frame of my

radiator-shield,) which is by me removably and adjustably attached to the radiator.

A letter of reference applied to a specific 55 part or portion of the radiator-shield is used to indicate such part or portion wherever the same appears throughout the several figures of the drawings.

A is the top main body of part of the radiator-shield, such body part extending from in front of the radiator over the top thereof and a short distance down the back.

A' is the back main body part of the radiator-shield extending from part or portion A to 65 near the floor or other base on which the radiator to which the device is attached is placed.

B is a casting against the side whereof adjacent to the radiator the main body part A is designed to abut, and b is a flange extending 70 around casting B, corresponding substantially with the shape of such top main body part A.

B' is a casting designed and adapted to be attached to casting B, and when so attached to 75 constitute an extension thereof, reaching to and resting upon the floor or base on which the radiator to which the device is attached is placed.

b' is a flange on casting B' on the side 80 thereof adjacent to the radiator. The body part A' is designed to abut against the side of casting B' adjacent to the radiator and may be secured, as by rivet b', to flange b'.

X is the radiator.

C is an extension of casting B, by means of which castings B B' are secured together through bolts D D extending through corresponding holes in extension C of casting B and casting B'.

E is a bolt having screw-threads e e thereon.

e' is the head of bolt E, and is of such shape as to fit against, when brought in close contact therewith, coils Y Y' of radiator X.

F is a post having a hole therein at one end 95 thereof and screw-threads in such hole corresponding with and fitting over screw-threads e e of bolt E.

G is a washer fitting over bolt E and designed to be forced against coils Y Y', and to 100 fit such coils as post F is screwed onto bolt E. It will be readily seen that as post F is turned onto bolt E, and washer G is thereby forced against the coils Y Y', the end e' of

such bolt E is drawn into close contact with such coils, and thereby post F is firmly secured in position on radiator X between such coils Y Y', and at any desired height from the 5 bottom of the radiator.

H is a slot in casting B.

II are ridges on the side of face of casting B. J is a casting having therein slots J' and J².

K K are ridges on the side of face of casting 10 J, corresponding with the ridges II on the side of face of casting B.

L is a screw-threaded bolt having head l, and M is a nut having threads therein corresponding with and fitting over the screw- 15 threads on bolt L. Bolt L is adapted to pass

through slots H and J', respectively, and when extended therethrough with the nut M turned tightly in place on such bolt to hold the face of casting J, adjacent to the face of 20 casting B, in close contact therewith. When

the casting J is held as above, (in close contact with casting B,) the ridges II or some thereof intermesh with the ridges K K or some thereof, and thereby upward or down- 25 ward movement of casting J on casting B is prevented. By loosening the nut M, on bolt L casting J can be adjusted either upward or downward in reference to casting B, such bolt L moving in slot J' and different ones

30 of ridges II and K K intermeshing, or to the right or left, bolt L moving in slot H.

Slot J², in casting J, fits over part f of post F, and hence such post forms the support or base for the casting B. Casting B' being at- 35 tached, as hereinbefore described, to casting B, and such casting B' extending to the floor or base on which radiator X is placed, the bottom or foot of such casting B', when such casting B' is, as is usually the case, attached 40 to casting B, forms a second point of support for the joint-castings B B', and such castings will remain firmly in place. Like castings B B' are, of course, applied to each end of the radiator-shield, body parts A A' extend- 45 ing from the castings at one end of the radiator to the castings at the other end thereof.

It will be readily observed that the castings B B' can, by means of the post F, secured, as described, to the radiator and the 50 adjustable casting J, be readily applied to the radiator and properly adjusted when such radiator is already in operative position without disturbing it or its connections.

Having thus described my invention, what

I claim as new, and desire to secure by Letters 55 Patent, is—

1. In a radiator shield support a casting having a horizontal slot therein, ridges on the side of the casting adjacent to the slot, a second casting having a slot therein and ridges 60 on the side thereof adjacent to such slot, such ridges intermeshing with the ridges on the first named casting, and extending substantially horizontally when so intermeshing a second slot in the second named casting ex- 65 tending upward from the bottom thereof and adapted to fit over a horizontal post forming the support of the castings; substantially as described.

2. In a radiator shield a casting having a 70 horizontal slot therein, ridges on the side of the casting adjacent to the slot, a second casting having a slot therein and ridges on the side thereof adjacent to such slot, such ridges intermeshing with the ridges on the first 75 named casting, and extending substantially horizontally when so intermeshing a second slot in the second named casting extending upward from the bottom thereof and an ad- 80 ditional casting attachable to the first named casting and forming a leg therefor adapted to rest on the floor on which the radiator to which the castings are attached is placed; substantially as described.

3. In a radiator shield a casting having a 85 horizontal slot therein, ridges on the side of the casting adjacent to the slot, a second casting having a slot therein and ridges on the side thereof adjacent to such slot, such ridges intermeshing with the ridges on the first 90 named casting, and extending substantially horizontally when so intermeshing a second slot in the second named casting extending upward from the bottom thereof, a vertically 95 adjustable post secured to the radiator sec- tions forming a support on which the cast- ings rest; substantially as described.

4. The combination with a radiator of a casting forming one end of a radiator shield, a second casting adjustably secured to the first named casting and a post adjustably secured to the radiator, such post forming a support on which the castings rest; substantially as described.

GEORGE E. DIXON.
